UNITED STATES PATENT OFFICE.

JOSEPH H. THOMPSON, OF JOPLIN, MISSOURI.

DESIGN FOR A COMBINATION DINNER-TRAY.

54,971.

Specification for Design.

Patented Apr. 20, 1920.

Application filed December 3, 1919. Serial No. 342,271. Term of patent 14 years.

To all whom it may concern:

Be it known that I, JOSEPH H. THOMPSON, a citizen of the United States, residing at Joplin, in the county of Jasper and State of Missouri, have invented a new, original, and ornamental Design for a Combination Dinner-Tray, of which the following is a specification, reference being had to the accompanying drawing, forming part thereof.

Figure 1 is a plan view of a combination dinner-tray embodying my design, and

Fig. 2 is an edge view thereof.

I claim:

The ornamental design for a combination dinner tray, as shown.

JOSEPH H. THOMPSON.

Witnesses:

GEO. P. WALKER,
Mrs. J. H. THOMPSON.
